US0D1016506S

(12) **United States Design Patent** (10) **Patent No.:** **US D1,016,506 S**
(45) **Date of Patent:** **** Mar. 5, 2024**

(54) **FOOTREST**

(71) Applicant: **SHENZHEN BESTQI INNOVATION TECHNOLOGY CO., LTD**, Shenzhen (CN)

(72) Inventor: **Bo Cheng**, Shenzhen (CN)

(73) Assignee: **SHENZHEN BESTQI INNOVATION TECHNOLOGY CO., LTD**, Shenzhen (CN)

(**) Term: **15 Years**

(21) Appl. No.: **29/843,343**

(22) Filed: **Jun. 21, 2022**

(51) **LOC (14) Cl.** **06-01**

(52) **U.S. Cl.**

USPC **D6/349**; D6/601

(58) **Field of Classification Search**

USPC D6/336, 349-353, 355, 360, 368, 373, D6/376, 685, 690, 691, 691.1, 691.8, D6/692.7, 708, 335, 381, 656.1, 656.16, D6/691.6, 691.9, 330, 596, 601; D23/296, 303, 309; D25/64, 65, 63; D21/690
